FIG. 1 is a top perspective view of an edible food product showing my new design;

FIG. 2 is a bottom perspective view thereof;

FIG. 3 is a top plan view; and

FIG. 4 is a bottom plan view thereof.

The present design is an edible food product which is characterized by a generally truncated conical shape the smaller end of which is generally semi-spherical. The food product is formed of relatively thick dough having a flaky appearance and texture and with a glazed and browned exterior crust. An overlapping fold line extends substantially the full length of the product.

The stippling on the drawing represents the browned and glazed outer surface.

I claim:

The ornamental design for an edible food product, as shown and described.
